RAIL BRACE

James H. Asselin, Winnetka, Ill.

Application July 18, 1944, Serial No. 545,419

9 Claims. (Cl. 238—292)

1

This invention relates to rail braces for railway track.

As a train approaches a section of track, it sets up in that track a vertical up-and-down "wave" or "floating" motion of the rail. Heretofore, rail braces have not, if at all, dealt satisfactorily with these motions. In known adjustable rail braces the objective has been to have the assembly very rigid, with the result that these motions were transmitted through the rail brace and tie plate to the tie or to the tie and ballast, with the result that excessive wear and pumping of ties and ballast occurred. Prior designs, based on rigidity of track, were unsound since rigidity could not be permanently maintained.

Since rail wave motion is inherent in train movement over track, the present invention is based on the importance and necessity of flexibility in track and aims to allow and control wave action instead of trying to eliminate it completely.

In accordance with the present invention such wave motion in a limited degree is permitted, but is controlled above the tie plates, and only a minor portion is permitted to transcend through the tie plates into the ties or through the ties to the ballast. By so controlling and limiting this motion, the wear will be between the rail and tie plate, or between steel upon steel. Thus wear on ties and loosening of ballast is greatly reduced.

As will later be more apparent, the invention incorporates a hinge action fastening means, which provides the flexibility necessary to coincide with the "wave" or "floating" action of the rail.

Moreover, a brace stop is included that extends downwardly over the tie plate and holds the brace member continually in place. This brace stop assures continuous contact of the brace against the rail, and prevents the brace member from moving longitudinally with the rail when the wedge is driven into place.

Moreover, many adjustable rail braces are provided with bolts and nuts. The latter must be tightened from time to time inasmuch as they loosen with vibration. Some types also employ bolts which are inserted from the bottom of the base plate and are thus complicated and costly to install. In those types employing a wedge tightened by a bolt there is a real danger that turning the bolt too tightly will tilt the rail inwardly.

Still further, adjustable rail braces now known and which use nuts and bolts or ratchet toothed

2

wedges or the like, are highly susceptible to wear, rust and corrosion due to weather conditions and salt brine. Many of them moreover are complicated by having too many parts, thus materially increasing the original cost, the cost of installation and the cost of maintaining proper adjustment.

These difficulties and disadvantages have been overcome by the present invention and it is a primary object of the invention to accomplish these aims.

A further object of the invention resides in providing a rail brace which may be used on switch rails, in turnouts, spring frogs, guard rails, curved rail in track, and on tangent track. Other uses will suggest themselves to those skilled in the art.

Records show that a large percentage of railroad accidents are the result of too wide track gauge. The gauge of track is frequently maintained by gauge rods which are connected to the base of one rail and with the base of the opposite rail. They are insulated when in a signal section area. Gauge rods have several defects. The insulation fouls, especially in wet weather, thus short-circuiting the signal system, but a more important defect is that the gauge of the bases only of the rails is maintained without assuring the gauge of the tops of the rails. The rail tops tip outwardly, thus throwing the rails out of gauge. Where, as in curves, frogs, guard rails and switch rails, the track is subjected to abnormal thrusts, the gauge of the rails thus frequently becomes too wide. In curves it has been found that the outward or side thrust of the wheels against the rail top sometimes causes the outer end of the base plate to cut into the tie to a depth of one-half (1/2) inch. This may result in widening the gauge, measured at the rail top, as much as one (1) inch. The present invention applied at these sections of track will avoid these disadvantages of gauge rods and will prevent too wide gauge.

In one preferred form the contacting surfaces of the brace member and of the wedge are curved in profile forming a type of cylinder and socket joint which makes possible a hinging movement of the brace member and permits a limited amount of wave motion of the rail to occur. The cylinder and socket joint provides the greatest possible wearing area between brace member and wedge, thus making the necessity of adjustment less frequent. Moreover, such a cylinder and socket structure provides the greatest possible amount of bearing surface to best withstand

stresses and strains in the device. It is an important object of the invention to provide such an arrangement.

The invention also has for an object the provision in one of its forms of a brace member which engages the rail only beneath the head and for a short distance down the web, said brace member being disposed in operation on a 45° line to provide a true bearing pressure against the web above the weakest section of the rail where the greatest bending stresses are present in the rail on curved track. The brace member in this form is urged toward the rail by a wedge. The constant brace pressure against the upper part of the rail web, maintains canted rails in alignment with the bevel tread wheels. This provides true bearing on the rail head for greater wear.

Another object of the invention resides in the provision having an extra long canted base tie plate. This distributes the bearing loads more uniformly over the tie contact area and prevents cutting into the ties, thus assuring greater accuracy and providing for longer life.

These and other objects and advantages of the invention will become more apparent from the following specification and claims when read on the accompanying drawings in which:

Fig. 1 is an end elevation of a rail brace constructed in accordance with one form of the invention, the rail being shown in section;

Fig. 2 is a side elevation of the same;

Fig. 3 is a side elevation of the brace member;

Fig. 4 is a top plan view;

Fig. 5 is a section taken on the line 5—5 of 35

Fig. 4;

Fig. 6 is an end elevation of a modified form;

Fig. 7 is a section taken on the line 7—7 of 40

Fig. 8 of a preferred embodiment;

Fig. 8 is a top plan view of a preferred embodiment;

Fig. 9 is an end elevation of the same;

Fig. 10 is a side elevation of the brace member shown in Figs. 7 to 9;

Fig. 11 is an end view of the same brace member and wedge (shown separated);

Fig. 12 is an end elevation of another form;

Fig. 13 is an end view of the brace member and wedge (separated) of a modified form;

Fig. 14 is an end elevation of still another modification;

Fig. 15 is a top plan view of a guard rail structure embodying the invention;

Fig. 16 is a section taken on the line 16—16 of 45

Fig. 15;

Fig. 17 is an end elevation of a rail brace according to another modification, the wedge being shown in section; and

Fig. 18 is a top plan view of the same.

Referring now more particularly to Figs. 1 to 5, inclusive, the numeral 10 indicates a railroad tie on which is disposed a metal base plate 11. The inner end of the base plate 11 is of slightly greater thickness than the remainder of the base plate and is provided with a transverse rail abutment 12 for the rail 13. The abutment may be integral with the base plate, or may be welded thereto as shown.

The rail 13 is secured to the tie by means of the spikes 14 which are driven into the tie through openings 15 in the base plate 11 until the heads of the spikes engage the base flanges of the rail. The base plate is also provided with openings 16 through which additional spikes (not

shown) may be driven into the tie to secure the base plate to the tie.

The base plate 11 near its outer end is provided with a rectangular block 17 disposed transversely of the base plate. The block 17 may be integrally formed with the base plate or may be welded thereto as shown. The inner edge of the block 17 and the rail engaging surface of the abutment 12 are parallel. For purposes of the invention the inner edge of the block 17 is cut with a rectangular groove 18.

The reference numeral 19 indicates the brace member proper. This is an irregularly shaped member having a solid portion 20, the base surface 21 of which is adapted to rest flush on the upper surface of the base plate 11. The solid portion slopes upwardly toward the rail head. The upper end of such portion is adapted to engage the under surface of the rail head.

The brace member 19 has integral webs 22 disposed in vertical planes. These extend below the sloping part of solid portion 20 and are provided with lower edges such as 23, which are shaped to conform to, and which are adapted to engage the upper surface of the flange of the base of the rail 13. It will be noted that the spacing of the webs 22 is such as to permit the brace member 19 to engage the rail without interference from the spikes 14.

The outer edge 24 of the solid portion 20 of the brace member 19 is vertical but the line of the edge is disposed at an angle with respect to the rail 13. This outer edge 24 is cut with a rectangular groove 25, which is in the same plane as the groove 18 in the block 17.

The brace member 19 is provided on one side portion with a laterally extending lug 26, which has a downwardly projecting flange 27. When the brace member 19 is in operative position, this flange 27 is adapted to engage the side edge of the base plate 11.

The rail brace structure is completed by a wedge member 28, the side edges 29 and 30 of which have intermediate laterally extending tongues 31 and 32, respectively, of rectangular section.

The wedge 28 is adapted to be driven in place in a horizontal plane in such manner that the tongues 31 and 32 are disposed respectively in the grooves 18 and 25. When so driven the side edge 29 of the wedge and its tongue 31 are, of course, parallel to the inner edge of the block 17. The other side edge 30 (of the wedge 28) and its tongue 32 are disposed with respect to the line of edge 29 at an angle complementary to the edge 24 of the brace member 19.

Obviously, as the wedge is driven in place the brace member 19 is forced against the rail 13 which it engages under the rail head and on the upper surface of the rail base, as shown in Fig. 5 for example.

The flange 27 on the lug 26 prevents the brace member 19 from moving longitudinally of the rail as the wedge 28 is driven in place.

The tongues 31 and 32 at the smaller end of the wedge 28 are provided with a plurality of vertical holes 33 (Fig. 4), which are staggered. After the wedge has been securely driven into place, a locking pin (not shown) may be passed through the first hole not covered so as to prevent an accidental blow on the wedge from dislodging it and loosening the assembly.

In accordance with a most important feature of the invention, the tongues 31 and 32 (see Figs. 1 and 5) are of a rectangular section which is slightly smaller than the cross section of the

grooves 18 and 25. In the early part of this specification reference was made to certain movements of the track section as a train approaches and passes. It was there stated that there is a vertical up and down "wave" or "floating" movement of the rail, which, in a limited degree, has been found to be necessary. Heretofore in rail braces the object has been to have the assembly so rigid that these motions are transmitted through the rail brace, and base plate, to the ties and ballast.

In accordance with the present invention by reason of the slight clearance of the tongues 31 and 32 in the grooves 18 and 25, a limited hinging movement of the wedge is permitted, thus allowing movement of the brace member 19 as the rail "waves" and "floats." At the same time the gauge of the rail, particularly at the rail head, is accurately maintained.

In Fig. 6 there is shown in side elevation a modified form which is identical with that shown in Figs. 1 to 5, inclusive, except for the form of the brace member.

In this form the brace member 34 is provided with a rail engaging portion which engages the under surface of the rail head and the upper portion only of the rail web, but at no other point. The brace member 34 is provided with an intermediate strengthening web 35.

It will be noted that the brace member is disposed substantially at a 45° angle to provide a true bearing pressure against the web at the weakest section of the rail where the greatest bending stresses are present on curved track.

In Fig. 6, as in other embodiments to be described, like parts are given the same reference numerals.

A preferred form of the invention is illustrated in Figs. 7 to 11, inclusive. In this modification the brace member 36 has a rail engaging portion adapted to engage the under surface of the rail head and the uppermost portion of the rail web. Moreover, as in Fig. 6, the brace member is disposed on a 45° angle. A strengthening rib 37 is provided.

The principal differences in this embodiment, however, reside in the shape of the contacting surfaces of the brace member 36 and the wedge member 38. The wedge 38 has its surface 39 which faces the brace member curved, and the brace member has a complementary curved surface 40 adapted to be engaged by the curved surface 39 of the wedge.

It will be noted that these curved contacting surfaces comprise a form of cylinder and socket connection between the brace member 37 and wedge 38 when the wedge is driven into place. This cylinder and socket connection allows the brace member to describe a hinging action as up and down wave motion of the rail occurs, while still enabling the device to maintain the gauge of the rail head accurately.

This cylinder and socket connection provides the greatest amount of bearing surface to best withstand stress and strains in the rail brace.

The greater the area of contact between the brace member and the wedge, the less frequently the brace need be adjusted. It will be noted that this type of connection also provides the greatest possible wearing area between brace member and wedge and thus should reduce readjustments to a great extent.

The modification illustrated in Fig. 12 also has this cylinder and socket type of connection of Figs. 7 to 11, inclusive, but differs in other re-

spects. The brace member 41 has portions 42 and 43 which respectively engage the under surface of the rail head and the upper surface of the base of the rail. Moreover, the brace member 41 is formed to receive one or more bolts 44 by which the brace member may in addition be bolted to the tie plate 11. While it is believed that bolts are not necessary to devices constructed in accordance with the invention, the railroads sometimes desire them.

It will be noted that in this embodiment, like in the others, the brace member is provided with a lateral lug 28 having a downwardly projecting flange 27 adapted to engage the side edge of the tie plate 11.

In known rail braces which are bolted to the tie plate by means of bolts inserted from underneath the tie plate a tight fit is invariably prevented because, as the wedge is driven and the brace member moves slightly longitudinally, the top of the bolts are moved longitudinally so as to become tipped slightly from the ideal vertical position. The nuts are then tightened with the bolts in such position with the result that vibration from a few train movements shift the bolts back to a vertical position, and they thus become loosened almost the very day they are installed.

In accordance with this embodiment of the present invention the flange 27 on lug 26 will prevent the brace member from moving longitudinally of the rail as the wedge is driven into place. Hence, the bolts 44 will be in the ideal vertical position when then tightened. This embodiment of the invention thus possesses the advantage of being a bolted brace which reasonably can be expected to be tight upon installation and which will not become loosened with the first several passages of a train. This is a very important consideration in the bolted type of brace.

Another modification is illustrated in Fig. 13. This modification is identical with that shown in Figs. 7 to 11, inclusive, except that the contacting surfaces of the brace member 45 and the wedge 46 are substantially < shaped in profile. This type of construction has many advantages.

The same type of < shaped contacting surfaces is present in the modification shown in Fig. 14. Here, however, the brace member 47 has portions 48 and 49 which respectively engage the under surface of the rail head and the upper surface of the base of the rail.

The rail brace described may be applied to tangent, curved rail in track, switch rails in turnouts, spring frogs and guard rails, as well as in other rail structure. An application of one form of the invention to a guard rail structure is illustrated by way of example in Figs. 15 and 16.

In the top plan view (Fig. 15), the main rail 50 rests on base plates 51, 52, 53 and 54.

Base plate 51 is provided with an abutment 55 which one edge of the rail engages. The rail is spiked to the tie (not shown) by the spikes 56 which pass through openings in the base plate 51. This base plate also supports the end of the guard rail 57. A filler block 58 is provided between the main rail 50 and the guard rail, the filler block being secured to the guard rail by the bolt 59 and nut 60. The side edge of the guard rail engages an abutment 61, preferably welded to the base plate 51, and a spike 62 passing through a hole in the base plate secures the guard rail with respect to the tie.

The main rail 50 and the guard rail 57 are

also separated by another filler block 63, which is secured to the guard rail 51 by means of the bolt 64 and nut 65.

The base plates 52, 53 and 54 are similar to the base plate 11 of Figs. 1 to 5, inclusive, except that they are longer and have a greater space between the abutments 66 and the blocks 67 than exists between abutment 12 and the block 17 in Figs. 1 to 5, inclusive. The brace members 68 and the wedges 69 in Figs. 15 and 16 may be identical with the brace members 19 and wedges 28 of Figs. 1 to 5, inclusive.

These rail braces in Figs. 15 and 16 operate in the same fashion as those previously described herein, except that in this instance the brace members engage the guard rail and thus clamp that rail and the main rail between the abutments 66 and the blocks 67.

It should be apparent that any of the forms of the invention shown in Figs. 1 to 14, inclusive, may be similarly employed for guard rails and in other rail structures where rail brace means are desirable.

Current day practice of rail inspection for defects and flaws is carried out with an inspection car provided with testing equipment operating on the magnetic field principle. The presence of an uninsulated rail brace, as on curves and the like, would increase the magnetic field and prevent accurate inspection with such equipment.

The embodiment of the invention shown in Figs. 17 and 18 avoids this disadvantage. Generally, the embodiment is similar to that illustrated in Figs. 7 and 8, but it provides an insulating member 70 which is disposed on the rail head engaging portion of the brace member 36. Such insulating member 70 prevents the rail brace from increasing the magnetic field during the testing of the rail.

It will be noted that the insulating member 70 also tends to reduce wear of the rail as well as of the brace member at the contact surfaces.

The insulating member may be of any suitable material which will accomplish these two purposes.

The embodiment of Figs. 17 and 18 also shows a modified form of joint between the block 71 and the wedge 72. The block is provided with a longitudinal recess or groove 73 which is frusto-conical in section and the wedge 72 is provided with a complementary frusto-conical sectioned ridge 74. The ridge 74, as will be seen, is slightly smaller in section than the groove 73.

In other respects the embodiment is about the same as that shown in Figs. 7 and 8.

Many applications of the present invention will now occur to those skilled in the art. The structure disclosed herein may be varied within the scope of the invention which is not to be limited except as indicated in the following claims.

What I claim is:

1. A rail brace comprising, a base plate adapted to be disposed beneath a railroad rail, said base plate having a raised abutment for engaging one edge of the rail base, a block rigid with the base plate and spaced from the opposite edge of a rail when said rail is disposed in place on said base plate, said block having a surface facing toward said rail, a brace member for engaging the rail, said brace member being positioned between the rail and said block and having a surface facing toward said block, the facing surfaces of said block and brace member being contained in non-parallel planes, the surface of said block facing said rail having a longitudinal groove of

rectangular section extending throughout its length, a wedge adapted to be driven horizontally between said block and said brace member, said wedge having side surfaces complementary to the adjacent surfaces of said block and said brace member, a rectangular sectioned tongue extending laterally from the side surface of the wedge adjacent said block for engagement within said groove when the wedge is driven into place, the cross sectional area of said groove being slightly larger than that of said tongue, the adjacent surfaces of said wedge and said brace member being complementary in profile.

2. A rail brace comprising, a base plate adapted to be disposed beneath a railroad rail, said base plate having a raised abutment for engaging one edge of the rail base, a block rigid with the base plate and spaced from the opposite edge of a rail when said rail is disposed in place on said base plate, said block having a surface facing toward said rail, a brace member for engaging the rail, said brace member being positioned between the rail and said block and having a surface facing toward said block, the facing surfaces of said block and brace member being contained in non-parallel planes, the surface of said block facing said rail having a longitudinal groove of rectangular section extending throughout its length, a wedge adapted to be driven horizontally between said block and said brace member, said wedge having side surfaces complementary to the adjacent surfaces of said block and said brace member, a rectangular sectioned tongue extending laterally from the side surface of the wedge adjacent said block for engagement within said groove when the wedge is driven into place, the cross sectional area of said groove being slightly larger than that of said tongue, the adjacent surfaces of said wedge and said brace member being provided with complementary profiles, the upper portion of one overlying the upper portion of the other when the wedge is driven into place.

3. A three piece rail brace comprising a base plate the upper surface of which is provided with first and second abutments spaced from each other and adapted when in operative position to be disposed on opposite sides of a rail with the first abutment engaging one edge of the rail base and the other being spaced from the opposite edge of the rail, a brace member having a portion for engaging the rail and a portion disposed on said base plate, said latter portion having a side surface facing said second abutment, the facing surfaces of said brace member and said second abutment being contained in non-parallel vertical planes, a wedge having side surfaces complementary to the facing surfaces of said brace member and said second abutment, a tongue and groove connection between said wedge and said second abutment, said groove having a vertical distance greater than said tongue and the contacting surfaces of said brace member and said wedge forming a pivot joint when the wedge is driven in place in a longitudinal direction between said brace member and said second abutment.

4. A three piece rail brace comprising a base plate the upper surface of which is provided with first and second abutments spaced from each other and adapted when in operative position to be disposed on opposite sides of a rail with the first abutment engaging one edge of the rail base and the other being spaced from the opposite edge of the rail, a brace member having a portion for engaging the rail and a portion disposed on

said base plate, said latter portion having a side surface facing said second abutment, the facing surfaces of said brace member and said second abutment being contained in non-parallel vertical planes, a wedge having side surfaces complementary to the facing surfaces of said brace member and said second abutment, a tongue and groove connection between said wedge and said second abutment, said groove having a vertical distance greater than said tongue, the surfaces of said wedge facing said brace member having a longitudinal groove substantially < shaped in profile, and the surface of said brace member facing said wedge having a complementary contour.

5. A three piece rail brace comprising a base plate the upper surface of which is provided with first and second abutments spaced from each other and adapted when in operative position to be disposed on opposite sides of a rail with the first abutment engaging one edge of the rail base and the other being spaced from the opposite edge of the rail, a brace member having a portion for engaging the rail and a portion disposed on said base plate, said latter portion having a side surface facing said second abutment, the facing surfaces of said brace member and said second abutment being contained in non-parallel, vertical planes, a wedge having side surfaces complementary to the facing surfaces of said brace member and said second abutment, a tongue and groove connection between said wedge and said second abutment, said groove having a vertical distance greater than said tongue, the facing surfaces of said wedge and said brace member being provided with complementary angular profiles for centering the wedge and brace member as the wedge is driven into place.

6. A three piece rail brace comprising a base plate the upper surface of which is provided with first and second abutments spaced from each other and adapted when in operative position to be disposed on opposite sides of a rail with the first abutment engaging one edge of the rail base and the other being spaced from the opposite edge of the rail, a brace member having a portion for engaging the rail and a portion disposed on said base plate, said latter portion having a side surface facing said second abutment, said last-named surface of said brace members having a groove of rectangular section, the facing surface of said second abutment having a similar groove, the

facing surfaces of said brace member and said second abutment being contained in non-parallel vertical planes, and a wedge having side surfaces complementary to the facing surfaces of said brace member and said second abutment, and tongues extending laterally from said wedge and adapted to be disposed in said grooves as the wedge is driven into place in a longitudinal direction between said brace member and said second abutment, said groove formed in said second abutment having a vertical distance greater than said tongue cooperating therewith.

7. A rail brace as defined in claim 3, the space on said base plate between first and second abutments being greater than the thickness of a main rail, a guard rail and an intermediate filler member, whereby the brace member may engage the guard rail and through the filler member brace the main rail.

15 8. A rail brace as defined in claim 3, said base plate having spike openings for rail spikes and said brace member having spaces on its underside in alignment with said spike openings, whereby said brace member may be positioned snugly against a rail with the rail spike located in said spaces.

20 9. A rail brace as defined in claim 3, said wedge comprising a single piece member, said brace member comprising a single piece member, and the engagement of said wedge between said second abutment and said brace member comprising the sole securing means for said wedge.
